COMBINED DIVING PLATFORM AND LADDER

Vernon A. Allison, Flint, Mich.

Application October 10, 1956, Serial No. 43,304

Term of patent 14 years

(Cl. D15—8)

The drawing is a perspective view of my combined diving platform and ladder secured to the side of a boat, the latter being shown fragmentarily in dotted lines for illustrative purposes only.

I claim:

The ornamental design for a combined diving platform and ladder, substantially as shown and described.
